UNITED STATES PATENT OFFICE

MICHAEL I. BROWNE, OF DELIA, KANSAS

INTERNAL-COMBUSTION ENGINE

Application filed September 13, 1927. Serial No. 219,355.

This invention relates to internal combustion engines operating on the two cycle principle, and has for its object to provide an internal combustion, two cycle engine capable of attaining high speed crank shaft rotation; which eliminates the wrist pin joint between the piston and connecting rod, thereby minimizing the friction on the cylinder wall; which employs an oscillating cylinder to usurp the function of a wrist pin joint, thereby permitting more durable bearings than are practical in a wrist pin joint; which employs mechanically operated valves; which is highly efficient in its scavenging action; which eliminates the necessity of timing gears and counter shaft in its valve operating mechanism.

The novel structure of this engine accounts for the following advantages; an unusually long stroke; high primary compression; a piston cooled by the inflowing combustible gases thereby eliminating preignition due to incandescent carbon on the piston head.

An examination of the specification and description of the method of operating will disclose other advantages not herein specifically pointed out, but which I will endeavor to enumerate in the appended claims. The numerical and alphabetical references in this specification are to the accompanying illustrations which are a part of this specification, and in which:

Figure 1 is a vertical transverse section in a plane parallel to the line of the crank shaft; Figure 2 is a vertical transverse section, at right angles to the plane of section in Figure 1, the crank shaft appearing in cross section of its crank pin.

Figure 3 is a plan view of the exhaust port, looking from above, showing the said port surrounded by a continuous packing strip;

Fig. 4 is a cross section of the continuous packing strip shown in Figure 3, with its thrust spring also shown in section.

The specification and drawing, herewith submitted in this application are for a vertical engine but I do not wish to be limited in the scope of this invention to a vertical engine, as horizontal mounting is equally feasible.

Referring to Fig. 1, the two side members 1 and 1L are secured at their base to base plate

41. Each of the side members 1 and 1L, have two apertures A and AL and 26 and 26L, the L referring to the member on the left. The apertures A and AL are provided for the purpose of receiving the crank shaft 4, 55 and to facilitate the insertion of the crank shaft bearing caps 2 and 2L respectively. The apertures 26 and 26L are provided to receive the cylinder hanger bosses 27 and 27L respectively. An arcuate cap member 24 securely attaches to the upper extremity of the side member 1 and in like manner to side member 1L. A cylinder 18 is mounted between the two side members 1 and 1L, by means of integral bosses 27 and 27L resting 60 on bearings in the apertures 26 and 26L respectively. An arcuate intermediate valve member 23, the contour of the upper surface of which conforms to the contour of the lower arcuate surface of the cap member 24 65 and is constrained in slidable proximity to the said cap member 24 by means of angle retainers integral with the said cap member, is situated slidably between the extremity of the head of cylinder 18 and the cap member 70 75. That portion of the ends of the arcuate intermediate valve member 23 which lies between the integral retention angles of the cap member 24, are bent downwardly to an extent and at an angle which will herein 80 later be more fully described. The head of cylinder 18 is preferably integral with the cylinder and converges to a boss-like extremity which gives a longitudinal rectangular section as is suggested in Fig. 3. The length 85 of this cylinder head extremity is such as to permit a sliding fit between the integral retention angles of cap member 24. In Fig. 1 the length appears equal to the outside 90 diameter of the cylinder. The boss-like extremity of the integral head of cylinder 18, is perforated to form port 20 which periodically coacts with the port 21 in the arcuate valve member 23 and port 22 in the cap member 24 to permit the interior of cylinder 18 95 to communicate with a suitable exhaust conductor pipe, not shown. The cylinder hanger boss 27L is perforated longitudinally at 32 to form part of a conductor passage, integral 100 with the cylinder preferably, terminating

in a port at the base of the cylinder, said port being controlled by the automatic poppet valve 29. The cylinder hanger boss 27 is also perforated longitudinally at 34, said longitudinal perforation communicating through a radial perforation with the space between the lower portion of the cylinder wall and the water jacket 19. A conductor 33 communicates, through a radial perforation in the cylinder hanger boss, with the space between the upper portion of the cylinder wall and the water jacket 19. Conductors 36 communicate with the water spaces in the boss like extremity 25, of the integral cylinder head of cylinder 18, and terminate in the lower portion of water jacket 19, discharging into the space formed between cylinder 18 and jacket 19. Conductors 36 are shown in Figure 2. Continuing the reference to Figure 2, an annular partition divides the space formed between the cylinder 18 and jacket 19 into an upper and lower portion. The annular partition is shown in section at 35 and lies in a plane at right angles to the cylinder bore. The said annular partition 35 is interrupted on either side, by the cylinder hanger bosses 27 and 27L, the said cylinder hanger bosses forming part of the partition. A flanged member 15, fixed to the lower extremity of the cylinder 18, is provided with integral tubular extensions, one on each face of the flange, which serve as a guide for the connecting rod 7. A packing nut 16 threadably connects with the exterior tubular extension of member 15 and serves to compress the packing 28 around connecting rod 7. The connecting rod 7, at its upper extremity carries an enlarged portion, preferably integral, which forms a piston. The piston with its compression rings 72 are inserted in the cylinder from the lower end of same and the flange member 15 slipped over the connecting rod 7. Bolts 17 secure flanged member 15 to the lower extremity of cylinder 18. Packing 28 and packing nut 16 are placed as shown in the Figure 2. Prior to inserting the piston in the cylinder the valve assembly consisting of valve 14 with its integral flare 80, valve guide 13, valve spring 12 and valve spring retaining disk 11 are inserted in the tubular connecting rod as shown in Figure 2, the valve 14 seating in the port formed in the piston head. Dowel pin 81 retains valve guide 13 in position. Valve push rod 8 having two enlarged portions for bearings and carrying valve adjusting screw 9 with its lock nut 10, is inserted in the tubular connecting rod through the open lower extremity. The internally flanged nut 71 is threadably assembled to connecting rod 7, the internal flange of said nut 71 partially obstructing the opening in the tubular connecting rod 7, but allowing the push rod roller 6 to protrude. The spindle pin of push rod roller 6, terminate in grooves in the wall of tubular con-

necting rod 7 and thus serve to prevent the push rod 8 from rotating. The internally flanged nut 71 is oblong in shape and carries two integral rods 70, Figure 1, which are movably secured to the crank pin of crank shaft 4 by means of bearing caps 74. The integral rods 70 give the internally flanged nut 71 a bifurcated character, thus permitting the integral cam 5 on the crank pin of crank shaft 4, to pass unobstructedly between the said rods during each revolution of the said crank pin.

The contour of the arced surface of the cap member 24, the intermediate valve member 23 and the boss like extremity 25 of cylinder 18, is determined by having them conform to the arc described by radii respectively, which focus at a point in a line which coincides with the longitudinal centers of the integral hanger bosses of cylinder 18, said bosses 27 and 27L being mounted centrally in bearings in apertures 26 and 26L respectively. It is obvious that the radius employed to determine the internal arc of cap member 24, is longer than the radius employed to determine the internal arc of intermediate valve member 23. The members 42 and 42L are secured to the base plate 41, side members 1 and 1L and cap member 24. They serve to complete the enclosure, thus with covers 40 and 40L over apertures A and AL the engine is thoroughly secured against the entrance of dirt and grit to the mechanism.

The location of the spark plug is indicated at 43 Figure 2. Fig. 4 is a cross section of the continuous packing strip 37 with a section of the thrust spring 39. This packing strip is inlaid in the arced surface of the boss like extremity 25 of cylinder 18, and conforms to the arc thereof. The packing strip 37 surrounds the port 20 in boss 25, Figure 3, and thrust against the internal arced surface of intermediate valve member 23.

The integral boss cylinder hanger 27L with the perforation 32 is extended sufficiently to receive an intake conductor leading from a carburettor, the union being of a packed joint nature which will permit the oscillating movement of the said cylinder boss 27L. The cylinder hanger boss 27 is likewise extended and also the conductor 33, the latter extending sufficiently further to pass through a cap connector union which joins perforation in the cylinder hanger boss 27, with a conductor running at right angles. The cylinder hanger boss 27 is packed where it enters the cap connector union in order to permit the cylinder hanger boss 27 to oscillate. The conductor 33 is also packed where it passes through the cap connector union in order to permit it to oscillate in unison with the cylinder hanger boss 27. An additional conductor is movably con-

nected to conductor 33, by means of packing, which connects to a suitable pump or circulating device. Lubrication is accomplished by splashing the oil supply resting on base plate 41, and through an oil supply fed to the intake manifold passage connected to cylinder hanger boss 27L.

This specification is descriptive of a single cylinder but it is obvious that the invention disclosed can be utilized in the construction of a multicylinder engine and its application in the multicylinder field will be very practicable.

In the operation of this internal combustion engine, the integral piston of connecting rod 7 is moved forward in the cylinder and the vacuum thereby produced in the lower portion of the said cylinder causes an inflow of combustible fuel from the carburetor through the passage 32. When the crank pin of the crank shaft 4 passes the upper dead center the connecting rod 7 attached thereto causes the integral piston to accomplish a down stroke which compresses the combustible gas drawn into the lower portion of the cylinder, the automatic check valve 29 cooperating to accomplish this action. When the crank pin of the crank shaft 4 is at lower dead center the cam 5 on the said crank pin forces the roller 6 and consequently the push rod 8 forward, causing the valve 14 to lift from its seat in the head of the integral piston of connecting rod 7. The compressed gas is thus forcibly injected into the combustion chamber above the said piston and directed against the inner surface of the wall of cylinder 18, by the flare 80 on valve 14. At an early stage in the return stroke of the piston the valve 14 closes by virtue of the cam 5 passing from under roller 6 due to the revolving movement of the crank pin of crank shaft 4. The gas is now compressed above the integral piston of the connecting rod 7, and a new charge is drawn into the lower portion of the cylinder. When the crank pin again reaches the upper dead center or shortly thereafter, the charge is fired by means of a suitable ignition device, preferably a spark plug as indicated at 43, the explosion forcing the piston downward on its power stroke and repeating the compression cycle above described, and for the purpose of distinction here referred to as the primary compression. During the downward or power stroke of the piston until the crank pin of the crank shaft 4 stands at 90°, the cylinder 18 moves on its hanger bosses 27 and 27L, the said movement causing the cylinder head extension 25 to engage the down bent ends of the intermediate valve member 23 and exert a traction thereby on the said valve member 23 which finally brings the port 21 of the valve member 23 into conjunction with the port 22 of the cap member 24. The next 90° movement of the

crank pin of the crank shaft 4 causes a reverse movement of the cylinder 18 on its hanger bosses 27 and 27L which movement finally brings the port 20 of the cylinder head extension 25 into conjunction with the ports 21 and 22 previously alined. This permits the burned gases to exhaust from the combustion chamber through the passageway formed by the conjunction of these three ports, viz, 21, 22 and 20. The next 90° of revolution of the crank pin of crank shaft 4, serves to continue the movement of cylinder 18 on its hanger bosses 27 and 27L. Because of this movement and by virtue of the cylinder head extension 25 acting on the downward bent end of the intermediate valve member 23 which is nearest the port 21, the said intermediate valve member is retracted thus moving the ports 21 and 22 from conjunction and closing the port 22 as a consequence. When the port 20 and also 21 were in the process of transition across port 22, the valve 14 in the head of the integral piston of connecting rod 7, was held in an open position by the action of cam 5 and by the pressure of the gas confined in the lower part of cylinder 18 in the process of its primary compression as before described. As the burnt gases escape through the conjoined ports 20, 21 and 22, the fresh charge enters through the port in the piston head controlled by said valve 14, and is directed against the walls of cylinder 18 by the flare 80 on the head of valve 14. The friction of the wall of cylinder 18 retards the forward movement of the fresh charge of gas and serves to promote the removal of the burnt gas. This process results in a high degree of scavanging efficiency. A metal cloth 38 serves to prevent a preignition of the fresh gas while in the lower portion of the cylinder. The passage of the fresh charge of gas through the port in the piston head serves to cool the piston head and also valve 14 and thus prevent carbon knocking due to incandescent carbon thereon. Shortly after the crank pin of crank shaft 4 passes lower dead center, the conjunction of ports 20, 21 and 22 is interrupted. The exhaust action is thereby terminated and the secondary compression of the fresh charge is begun and continues until the crank pin reaches upper dead center at or near which point the charge is ignited and the cycle just described is repeated. It is of assistance to note, in the study of the operation of this engine that the ports 20, 21 and 22 are in conjunction while the crank pin is at or near lower dead center. When the crank pin is at any other point in its revolution there is no available avenue for the gas charge to escape. The intermittent action of the intermediate valve member 23 is mechanically accomplished by virtue of the oscillating movement of the cylinder 18 on its integral hanger bosses 27 and 27L.

5 The circuit of the cooling medium is through the conductor 33, the upper portion of the cylinder jacket enclosure, thence through conductors 36 leading from the cylinder head boss 25 to the lower portion of the cylinder jacket enclosure and finally through perforation 34 in cylinder hanger boss 27, to the radiator.

I claim—

- 10 1. In an internal combustion engine, an inclosed assembly consisting of a cylinder, a head on said cylinder, an arcuate extremity on extension boss on said head, the contour of said arcuate extremity conforming to the arc of a circle described by a radius focused in and at right angles to a line which is the common axis of diametrically opposed radiating bosses integral with the aforesaid cylinder, a piston reciprocally operable in said cylinder, 15 a perforated rod integral with said piston, said perforated rod reciprocally operable in a guide secured to the base of the aforesaid cylinder, a bifurcated end member secured to said perforated rod, the rods of said bifurcated end member revolvably secured to the crank pin of a crank shaft, said crank shaft and aforesaid cylinder rotatably and rockably mounted, respectively, in and between side members, said side members secured to and mounted on a base plate, an arcuate cap member secured to and mounted on side members, the contour of said arcuate cap member conforming to the arc of a circle described by a radius focused in and at right angles to a line 20 which is the common axis of the aforesaid diametrically opposed radiating bosses on the aforesaid cylinder when said cylinder is mounted between said side members, strip members secured to the aforesaid base plate, to the aforesaid arcuate cap member and to the aforesaid side members, the covers over apertures in said side members completing the inclosure.

25 2. In an internal combustion engine, an assembly consisting of a base plate, side members secured to and mounted on said base plate, an aperture in each of said side members with a bearing located in each of said apertures respectively, a crank shaft rotatably mounted on said bearings and a cam protuberance mounted on the bearing surface of the crank pin of said crank shaft.

30 3. In an internal combustion engine, a cylinder, a head integral with said cylinder, a boss on said head, an arcuate extremity on said boss, the contour of said extremity conforming to an arc described by a radius focused in and at right angles to a line passing diametrically through said cylinder; a pair of annular radially arranged diametrically opposed, longitudinally and radially perforated bosses integral with said cylinder in a position concentric with the arcuate extremity of the boss on the head of said cylinder, the common axis of the said diametrically opposed

bosses being the aforesaid line passing diametrically through the aforesaid cylinder.

35 4. In an internal combustion engine, an assembly consisting of a base plate, side members secured to and mounted on said base plate, an aperture in each of said side members with a bearing located in each of said apertures, a cylinder mounted in said bearings by means of a pair of annular radially arranged bosses integral with said cylinder at 75 diametrically opposed points, said cylinder being free to perform an oscillating movement by means of said annular radiating bosses being rotatably constrained in said bearings in a position of concentric relation to an arcuate cap member mounted on the aforesaid side members.

40 5. In an internal combustion engine, an assembly consisting of a base plate, side members secured to and mounted on said base plate, an aperture in each of said side members with a bearing located in each of said apertures respectively, a crank shaft rotatably mounted on said bearings, a cylinder movably mounted between said side members by means 85 of annular diametrically opposed radially arranged bosses rotatably constrained in a position of concentric relation to an arcuate cap member mounted on the aforesaid side members, a piston operable in said cylinder, a perforated connecting rod integrally attached to said piston, a bifurcated element secured to the end of said perforated connecting rod, a bearing including a cap, in each rod of the bifurcated element respectively, said bearings 90 being revolvably attached to the crank pin of the aforesaid crank shaft, a cam on said crank pin revolvably operable between the bearings of the rods of the said bifurcated element by virtue of the revolving crank pin. 100

45 6. In an internal combustion engine, an inclosed assembly consisting of a cylinder, a head on said cylinder, an arcuate extremity on the extension boss of said head, the contour of said arcuate extremity conforming to the arc of a circle described by a radius focused in and at right angles to a line which is a common axis of diametrically opposed annular radiating bosses integral with the aforesaid cylinder, a piston reciprocally operable in said cylinder, a perforated rod integral with or rigidly secured to said piston, said perforated rod reciprocally operable in a guide secured to the base of the aforesaid cylinder, a bifurcated end member secured to the said perforated rod, the rod of said bifurcated end member revolvably secured to the crank pin of a crank shaft, a cam on said crank pin revolvably operable between the rods 110 of the aforesaid bifurcated end member by 115 virtue of the revolving crank pin, said cam cooperating with a push rod to lift a combustible mixture inlet valve stem, said push rod and valve stem functioning within the said integral perforated rod; the aforesaid 120 125 130

- crank shaft and the aforesaid cylinder rotatably and rockably mounted respectively, in and between side members, said side members secured to and mounted on a base plate, 5 an arcuate cap member mounted on and secured to said side members, the contour of said arcuate cap member conforming to the arc of a circle described by a radius focused in and at right angles to a line which is a common axis of diametrically opposed annular radiating bosses integral with the aforesaid cylinder when said cylinder is mounted in the aforesaid side members, strip members secured to said arcuate cap member, to the 10 aforesaid base plate and to the aforesaid side members, the covers over apertures in said side members completing the inclosure.
7. In an internal combustion engine, an assembly consisting of a base plate, side 20 members secured to and mounted on said base plate, a cylinder movably mounted between said side members, a piston operable in said cylinder, a perforated connecting rod integrally attached to said piston, a flanged member secured to the base of the wall of the aforesaid cylinder, the aforesaid connecting rod reciprocally operable in opposed aligned perforated extensions on the faces of the said flanged member, one extension on each face 30 respectively.
8. In an internal combustion engine, an assembly consisting of a base plate, side members secured to and mounted on said base plate, a cylinder movably mounted between 35 said side members, a head integral with or secured to said cylinder, a perforated boss mounted on said head, said perforation communicating with the interior space of said cylinder and head, constituting a combustion chamber, an inlaid packing strip surrounding said perforation, a thrust spring underlying said packing strip, the exposed surface of said packing strip and the extremity of the aforesaid boss being arcuate in form, the contour being established by a radius at right angles to and focused in a line which is the common axis of the annular radiating bosses of the aforesaid cylinder.
9. In an internal combustion engine, an assembly consisting of a base plate, side members secured to and mounted on said base plate, a cylinder movably mounted between 50 said side members, an arcuate cap member secured to and mounted on said side members, a perforation in said arcuate cap member located centrally by a vertical line intersecting a line which is the axis of the annular radial bosses of said cylinder, an intermediate 55 arcuate valve member slidably mounted over the arcuate extremity of the aforesaid cylinder head boss by means of retainers integral with said arcuate cap member, a perforation in said intermediate valve member cooperable 60 with the perforations, in the said cylinder 65 head boss and in the aforesaid arcuate cap member respectively, conjunctively.
10. In an internal combustion engine, a base plate, side members secured to and mounted on said base plate, a cylinder movably mounted between said side members, a head integral with or secured to said cylinder, a boss mounted on said head, an arcuate intermediate valve member slidably mounted on said cylinder head boss, inwardly bent terminals on said intermediate valve member, said intermediate valve member functioning reciprocally by virtue of its inwardly bent terminals being alternately engaged by the boss on the head of the aforesaid movably mounted cylinder, said cylinder being constrained to an oscillating movement.
11. In an internal combustion engine, a cylinder, a piston reciprocally operable in said cylinder, a port in the head of said cylinder, a connecting rod integral with or secured to said piston, an aperture in said connecting rod adjacent the said port in cylinder head a port near the base of said cylinder, a valve controlling said port, a conductor connecting said port with an inlet to the longitudinal perforation in the annular radially arranged boss on the said cylinder, a two cycle principle of operation featured by a primary compression in the lower portion 90 of the said cylinder below the said piston, the injection of the primarily compressed fuel through the aforesaid aperture in the connecting rod and the port in the piston head successively, to the cylinder portion above 95 the said piston, utilizing the friction of the wall of said cylinder to retard the forward progress of the injected gas, means for directing the said gas against the cylinder wall, and means for exhausting the burned gases 100 through the port in the boss mounted on the head of the said cylinder.
12. In an internal combustion engine, an assembly consisting of a base plate, side members secured to and mounted on said base plate, a crank shaft mounted on bearing in said side members, a cylinder movably mounted between said side members, a piston operable in said cylinder, a connecting rod integral with or secured to said piston, said 110 connecting rod engaging the crank pin of the said crank shaft through the medium of a bifurcated end member, the aforesaid cylinder being constrained to an oscillating movement by virtue of the revolving crank 115 pin of the said crank shaft cooperating with the said connecting rod and the reciprocating movement of the said connecting rod, thereby produced.
13. In an internal combustion engine, a base plate, side members secured to and mounted on said base plate, an arcuate cap member secured to and mounted on said side members, a cylinder movably mounted between 120 said side members, a head integral with or secured to the cylinder, a piston operable in the cylinder, a connecting rod integral with or secured to the piston, a crank shaft 125 mounted on bearing in the side members, the connecting rod engaging the crank pin of the said crank shaft through the medium of a bifurcated end member, the cylinder being constrained to an oscillating movement by virtue of the revolving crank pin of the said crank shaft cooperating with the said connecting rod and the reciprocating movement of the said connecting rod, thereby produced.

with or secured to said cylinder, a boss, having an arcuate extremity, mounted on said head, an arcuate intermediate valve member movably mounted on the arcuate extremity of said boss, the several arcuate surfaces co-
5 operating herein, being concentric, their radii being protracted at right angles to and focused in a line which is the axis of the aforesaid diametrically opposed annular radiating bosses of the aforesaid cylinder.

10 MICHAEL I. BROWNE.
